FURNITURE LEG

Robert E. Kjer Jakobsen, Manhattan Beach, Calif., assignor to Virtue Bros. Mfg. Co., Los Angeles, Calif., a corporation of California

Filed Feb. 12, 1960, Ser. No. 59,367

Term of patent 14 years

(Cl. D33—14)

Fig. 2 is a side elevational view of said leg;

Fig. 3 is a top plan view of said leg; and

Fig. 4 is a bottom plan view of said leg, the foot being eliminated from this view for clarity.

The dominant feature of my design resides in that portion shown in full lines on the drawing.

I claim:

The ornamental design for a furniture leg, substantially as shown and described.
